Patented Feb. 10, 1885.# UNITED STATES PATENT OFFICE.

CHARLES T. GROSJEAN, OF NEW YORK, N. Y., ASSIGNOR TO TIFFANY & CO.,
OF SAME PLACE.

DESIGN FOR A SPOON-HANDLE.

SPECIFICATION forming part of Design No. 15,785, dated February 10, 1885.

Application filed October 14, 1884. Term of patent 14 years.

To all whom it may concern:

Be it known that I, CHARLES T. GROSJEAN, a citizen of the United States, residing in the city, county, and State of New York, have 5 invented and produced a new and original Design for Spoon-Handles or other Articles of Table-Service, of which the following is a specification, reference being had to the accompanying drawings, forming part thereof.

10 The design for this spoon-handle consists in the figure of a North American Indian, with the ornamental decoration as exhibited on the blanket, basket, tent, paddle, head, and feather-work, &c., of same. The Indian is placed in the head of the spoon at the top of the shank.

15 In the several spoons composing the set the Indian is represented as in the various war-dances.

In the drawings, Figures 1 and 12, inclusive, are front views of the handles, representing the Indian in and clothing and equipment for twelve dances. Figs. 13 to 24, inclusive, are views of the reverse sides of said handles shown in Figs. 1 to 12.

20 Fig. 1 represents a front view of the Indian in the scalp-dance in the flat. Fig. 13 is a rear view thereof.

Fig. 2 represents a front view of the Indian in the medicine-dance in the flat. Fig. 14 is 30 a rear view thereof.

Fig. 3 represents a front view of the Indian in the buffalo-dance in the flat. Fig. 15 is a rear view thereof.

Fig. 4 represents a front view of the Indian 35 in the chief-dance in the flat. Fig. 16 is a rear view thereof.

Fig. 5 represents a front view of the Indian in the slave-dance in the flat. Fig. 17 is a rear view thereof.

Fig. 6 represents a front view of the Indian 40 in the discovery-dance in the flat. Fig. 18 is a rear view thereof.

Fig. 7 represents a front view of the Indian in the bear-dance in the flat. Fig. 19 is a rear view thereof.

45 Fig. 8 represents a front view of the Indian in the pipe-dance in the flat. Fig. 20 is a rear view thereof.

Fig. 9 represents a front view of the Indian in the coon-dance in the flat. Fig. 21 is a rear 50 view thereof.

Fig. 10 represents a front view of the Indian in the beggar-dance in the flat. Fig. 22 is a rear view thereof.

55 Fig. 11 represents a front view of the Indian in the bull-dance in the flat. Fig. 23 is a rear view thereof.

Fig. 12 represents a front view of the Indian 60 in the eagle-dance in the flat. Fig. 24 is a rear view thereof.

I claim—

The design for a spoon-handle, representing in the head thereof at the top of the shank an Indian, substantially as shown and described.

CHARLES T. GROSJEAN.
